UNITED STATES PATENT OFFICE

2,480,699

BUILDING ROOF CONSTRUCTION

Nolan S. Black, Highland Park, Mich., assignor
to National Steel Corporation, a corporation of
Delaware

Application February 21, 1946, Serial No. 649,162

15 Claims. (Cl. 108—1)

1
This invention relates generally to buildings and more particularly to factory fabricated roof structure therefor.

In the past, buildings of various kinds have been proposed in which the structural members therefor are factory preformed, ready to assemble in order to decrease the time and consequently the cost of building erection. In some instances, emphasis has been placed on the reduction in the time and cost of erection of such buildings to the detriment of good sound construction, particularly with respect to roofs with the result that many of such buildings were not leakproof. In other instances where particular attention was given to assure leakproof roofs, it has usually resulted in sacrificing low fabrication costs, or in rendering erection difficult and expensive, or both.

Accordingly, it is an object of the present invention to provide a new and improved low cost, readily erected roof and yet one which is leakproof.

Another object of the present invention resides in the new and improved arrangement between roof structural members to insure a leakproof roof.

Another object of the invention is to provide a new and improved panel connecting and ridge construction for insuring a leakproof roof.

A further object of the invention is to provide new and improved roof panels which may be readily secured in place and co-operate with other roof structure to insure a leakproof roof.

Other objects of the invention will become apparent from the following detailed description taken in connection with the seven sheets of drawings in which:

Figure 1 is a fragmentary perspective view of a building having a roof embodying features of the present invention;

Figure 2 is a fragmentary plan view of the building roof;

Figure 3 is a fragmentary isometric view, partly in section, of the roof at one side edge thereof;

Figure 4 is a fragmentary isometric view of a central portion of the roof shown partly in section;

Figure 5 is a fragmentary isometric view showing one corner of the roof;

Figure 6 is a fragmentary isometric view broken away and partly in section of the roof at one end of the building;

Figure 7 is a fragmentary cross-sectional view of the roof, taken along the line 7—7 of Figure 2;

Figure 8 is a fragmentary cross-sectional view of the roof, taken along the line 8—8 of Figure 2;

2
Figure 9 is a view in section of the roof, taken along the line 9—9 of Figure 2;

Figure 10 is a view in cross-section of the roof, taken along the line 10—10 of Figure 2;

Figure 11 is an isometric view of one of the roof panels, shown removed from the roof, and

Figure 12 is an isometric view of a panel connector member, shown removed from the roof.

In the drawings, which illustrate a preferred form of the invention, a building, shown in part in Figure 1, includes side walls 10, end walls 11 and my roof, designated generally by the numeral 12. The building walls 10 and 11 may be of any suitable construction and may be supported on any suitable supporting structure or foundation. The roof 12 comprises, in general, a ridge member 13, a plurality of roof panels 14, a longitudinally extending panel connector member or ridge cap 15 and a plurality of laterally extending panel connector members 16.

The ridge member 13 is supported adjacent its opposite ends on the building end walls 11 and in turn supports the inner or upper ends of the roof panels 14 which extend downwardly to and overhang the opposite side walls 10 on which they are also supported. Preferably, the roof panels 14 are rectangular and preferably they extend lengthwise between the ridge member and the side walls with side edges of adjacent panels in spaced opposed relation. The ridge cap 15, extending longitudinally of the roof, fits over or caps the ridge member 13. On opposite sides of the ridge member, the ridge cap 15 seats on the panels 14 near the upper end edge portions thereof, along the entire length of the roof to effect leakproof construction. As shown, the laterally extending panel connector members 16 extend from the ridge cap 15 to which they are connected to the outer side edges of the roof panels 14, overlying respectively the spaces between side edges of the adjacent panels, connecting the panels together in a fluid-tight manner.

In the present construction, opposite ends of the ridge member 13 project externally of the building beyond the end walls thereof, seating on brackets 17 which may be bolted or otherwise secured to the building end walls 11. Each of the brackets 17 includes a horizontal support or leg 18 on which the ridge member seats. Integral with the leg 18 are upstanding opposite side walls 19 and an upstanding end abutment 20 forming a retaining socket for the projecting end portions of the ridge member 13. These side walls 19 and the abutment 20 restrain side and end movements respectively of the ridge member 13 and

these side walls 19 and the abutment 20 in part form a casing for the projecting end portions of the ridge member. The side walls 19 of the brackets preferably extend upwardly and inwardly of the inner edges of the panels 14 to provide weather-tight construction.

The ridge member 13 comprises a pair of laterally spaced, elongated frame members 21 of C-shape cross-section which are spaced apart and connected together by spacer members 22, located at intervals along the length of the frame members. These frame members 21 and the spacer members 22 are preferably of steel construction for strength and durability, and may be welded or may be otherwise suitably secured together at the factory to provide a rigid unitary structure which may be readily swung into place at the erection site. Each of the frame members 21 is provided with outturned upper and lower side reinforcing flanges 23 and 24 respectively, the upper flanges 23 preferably having outer portions turned down, as at 25, and the lower flanges 24 preferably having outer portions turned up, as at 26.

The roof panels 14 each may be constructed of a pair of thin wooden panels 27 secured to opposite sides of a wooden frame 28 which preferably includes a drip moulding strip 29 forming the outer or lower edge of the panel. The wooden panels 27 and its frame 28 may be nailed, cemented, or be otherwise suitably secured together. In order to insure a leakproof panel and further to insure fluid-tight joints between the panels, connector members and associated structure, each of the panels 14 has its upper surface covered by a metallic cover sheet 30, preferably steel, having an upturned guard flange 31 along the inner or upper edge of the panel and upturned guard flanges 32 at the side edges of the panel except for the outer side edges of the end panels. These upturned side and end edge guard flanges are preferably welded together at the corners. By forming these upturned flanges 31 and 32 out of the metallic cover sheet 30 instead of providing flanges separate therefrom, no exposed edges are made available under which water might seep. At the outer side edges of the end roof panels, the metallic cover sheet 30 is bent down and under the panel edge to seal the interior of the panel and further to effect a finished side edge. Also, except for these outer side edges of the end panels, the side edge of each panel is provided with a facing and reinforcing strip 33. These facing and reinforcing strips 33 are preferably sheet steel angle strips having one leg seating flat against a side edge of a panel where it may be secured thereto by screws or by other suitable means. The side edge facing strips 33 extend upwardly above the upper surfaces of the panel 14 in engagement with the outer surfaces of adjacent upturned flanges 32 which thus seal the joints between the facing strips and the panel edges covered thereby. In mass production of the panels 14, it may be desired to form the cover sheet 30 with the facing strips 33 as integral parts thereof or joined to the upturned flanges 32. The facing strips 33, projecting above the upper surfaces of the panels in engagement with the outer surfaces of the sealing flanges 32 also serve to reinforce these flanges against being bent outwardly. To seal further the interior of the panel 14 against entrance of moisture, the metallic sheet covering 30 is bent down over the outer or lower edge of each panel, as at 34, and wrapped around and

under the drip moulding strip 29 as clearly shown, for example, in Figure 3.

Carried by each of the roof panels 14, at the upper or inner edge thereof, is a hanger member 35 for readily attaching the panel to the ridge member 13 and for locating the panel in the proper desired position laterally or crosswise of the roof. The hanger member 35 comprises a web portion 36, a lower, laterally extending flange 37 and an upper oppositely directed flange 38 having a downturned portion 39. This hanger member 35 preferably extends uninterrupted along the entire width of the panel with the web portion 36 flat against the inner end edge of the panel. The lower flange 37 of the hanger member 36 seats against the underside of the panel and may be apertured to receive wood screws for securing the hanger to the panel or the parts may be secured together by any other suitable means. Preferably, the hanger web portion 36 and the side edge facing strips 33 are welded together at the corners formed thereby. As shown, the hanger web portion 36 extends above the upper surface of the panel in back to back relation with the upturned flange 31 of the panel cover 30. The hanger web portion 36 reinforces the cover flange 31 and, in addition, co-operates therewith to prevent entrance of moisture into the panel along the end edge thereof. The upper laterally extending flange 38 seats on the upper edge portion of the ridge member 13 with the downturned flange portion 39 fitting against the inner surface of the ridge frame member. Thus, an upper portion of the web 36, the upper flange 38 and the downturned portion 39 co-operate to form a downwardly facing channel or hook to engage the upper portion of one or the other of the ridge frame members 21. In addition to the above functions of the hanger member 35, it will be seen that the hanger member also restrains endwise movement of the panel providing for locating and holding the panel in place without need of additional securing means, thus effecting a time saving in erection of the building.

The panel connector or ridge cap 15 is a hollow, elongated member preferably having a top wall 41, side walls 42 and a recessed bottom wall 43. Between the top and bottom walls of the ridge cap 15, a suitable wooden filler structure 44 is preferably provided for added strength and rigidity. In the present construction, the ridge cap 15 includes an upper, outer sheet metal casing fitting tightly over a lower sheet metal casing to provide the recessed bottom wall 43 and support for the wood filler. The side walls of the telescoping casings extend downwardly below the recessed bottom wall 43 and have outturned flanges 45, 46 with the outer casing flanges 45 seating on the upper surfaces of the inner casing flanges 46 which in turn seat on the upper surfaces of the roof panels 14. The ridge cap 15 encloses the upper portion of the ridge member 13, upper portions of the hangers 35 and also encloses the upturned panel guard flanges 31. At its opposite ends, the top wall 41 of the ridge cap 15 may have extended portions of its top wall 41 bent down, as at 41', co-operating with the bracket leg 18 and side walls 19 to provide casings enclosing the projecting end portions of the ridge member 13. As is more clearly shown in Figure 12, clearance cutouts 50 are provided in the ridge cap flanges 45, 46 and extend part way up the sides 42 of the ridge cap to clear the upturned panel flanges 32 and adjacent facing strips 33.

Carried by the ridge cap 15 to draw and hold

it down tightly against the roof panels, there is a plurality of depending rods 51 in spaced relation along the ridge cap. The rods 51 are T-shaped, in the present instance, having an upper transverse rod portion 52 held in aligned bearings 53 carried by a plate 54 which may be welded to the underside of the member recessed wall 43. Positioned between the spaced, ridge frame members 21, the rods 51 extend downwardly through apertures in abutment members or clamps 55 which seat against the lower edges of the frame members 21. Wing nuts 56 may be threaded onto the lower ends of the rods 51 and tightened down against the abutment members 55, thus drawing the ridge cap 15 down toward the ridge member 13. The abutment members 55 are preferably inverted, U-shaped metallic strips having opposite sides 57 fitting snugly between the opposed surfaces of the ridge frame members 21, thus additionally strengthening the ridge member. At their lower ends, the abutment member sides 57 are provided with outturned flanges 58 to engage against the undersides of adjacent panels.

A plurality of extension connector or closure members 60 are provided for respectively closing the inner open ends of the laterally extending panel connectors 16. These individual closure members 60 are carried by the ridge cap 15, extending laterally from opposite sides thereof, respectively, to receive or fit over inner end portions of the panel connector members 16 to insure weathertight connections therewith. Preferably, the closure members 60, in conformity to the general rectangular cross-sectional shape of the connector members 16 are hollow, each having a top wall 61 and opposite side walls 62. At the inner ends of the closure members 60, the side and end walls thereof may be provided with outturned flanges 63 which may be welded or be otherwise suitably secured flat to the connector member side walls 42 and the sides 62 may be welded at their lower edges to the connector member flanges 45, 46.

Each of the laterally extending connector members 16 is preferably hollow and includes an elongated casing or cover preferably formed of sheet steel having a top wall 65 and side walls 66, as shown more clearly in Figure 10. The side walls 66 of the connector member 16 position outwardly of or enclose the upstanding side edge panel flanges 32 and the panel facing strips 33 to cooperate therewith to effect weathertight joints. Each of the connector members 16 may be provided, as in the present construction, with a filler 68 which may be insulation material, wood or any other inexpensive material which will give added strength and rigidity to the connector. At their outer ends, each of the connector members 16 is provided with an extended portion 64 of its top wall 65 bent down and under the panel edges and then up and along the underside thereof as at 64', Figure 7. This forms a hooked end on the connector members 16 to hook under the outer edges of the panels 14 and overlie and close the opening between the spaced side edges of the panels which lie outwardly of the building side walls 10. In spaced relation along the length of each connector member 16, there is a plurality of depending connecting rods 69 having their upper ends secured to and between depending legs 70 of a pair of angle members 71 which may be welded or be otherwise suitably secured to the underside of the connector member top wall 65. These rods 69 extend downwardly respectively

through apertures in individual abutment members or clamps 72 and have lower threaded ends to receive nuts 73 which may be of the wing type, as shown. The abutment members or clamps 72 may each be formed of a strip of sheet steel bent transversely to provide, when in position, an inverted U-shaped member having a top or web portion 74 through which the rod 69 extends and against the underside of which the nut is tightened. Downturned sides 75 of the abutment 72 serve to space and locate the panels 14 relatively to each other and outturned lower flanges 76 abut the under surfaces of the facing strip flanges. The abutment members 72 and wing nuts 73 may come assembled with the connector members 16, as the widths of the abutment members may be such as to permit them to be swung around on the rods 69 to positions where they will pass through the openings between spaced side edges 20 of the panel or the clamp and nut may be assembled on the rod after the connector member is placed in its approximate position on the panels. In erecting the roof, the ridge member 13 is first erected merely by lowering it until it seats 25 on the brackets 17 with opposite end portions of the ridge member locating in the bracket retainers formed by the upstanding side walls 19 and end abutment wall 20. The ridge member 13 is held against side and end movement solely by these 30 socket type retainers, thus eliminating time and expense of bolting or otherwise securing this ridge member to the building walls. The roof panels 14 may now be lifted into place and their individual hangers 35 hooked over the upper portions 35 of the ridge member 13 which supports the panels adjacent their inner end edges, the panels being further supported adjacent their outer end edges on the building side walls 10. These hangers 35, in addition to supporting the inner ends of the 40 panels 14 on the ridge member 13 below the upper edge thereof, also locate the panels transversely of the roof and restrain movement of the panels in this direction. With the panels 14 in their approximate relative position in the roof assembly, 45 the panel connector members 16 can now be added. These connector members 16 are each swung to a position with the inner end raised so that the outer end may be hooked under the overhanging outer edges of the panels 14 and the 50 connector member is then lowered onto the roof panels overlying the space between the spaced side edges of a pair of adjacent panels. In this position, the connector member 16 fits over and encloses the upstanding panel guard flanges 32 55 and the facing strips 33 carried by the adjacent edges of the pair of panels and seats against the upper surfaces of the panels. The abutment members or clamps 72 which may be carried by the connector members 16 as a part of its assembly are swung around to engage opposed surfaces of adjacent panel facing strips 33, thus 60 spacing the panels 14 the proper distances apart with the outturned flanges 76 engaging the underside of the panels. The wing nuts 73 are now 65 tightened down, drawing the connector members 16 down tightly against the upper metallic surfaces of the panels 14 to form leakproof joints therewith. If, for any reason, moisture should find its way under the lower edges of the connector member sides 66, it will be seen that entrance of the moisture into the building will be 70 prevented by the upstanding panel guard flanges 32. After the laterally extending panel connectors 16 have been secured in place, the ridge cap 75 15 is lowered into place to complete the roof.

This ridge cap 15 fits over upper portions of the ridge member 13 and straddling it seats on the upper surface of the panels along the entire roof thus serving as a panel connector member. The ridge cap 15 also fits over and encloses the upstanding panel guard flanges 31 extending along the inner edges of the panels. Also, the closure members 60 carried by the ridge cap 15 respectively fit over and enclose inner end portions of the laterally extending connector members 16. The abutment members or clamps 55, carried by the connecting rods 51, are turned around so that their outturned flanges 58 engage under the lower edges of the ridge member 13 and the wing nuts 56 are tightened down to draw the ridge cap 15 down tightly against the roof panels 14. Thus, it will be seen that the ridge cap 15, the panel connector members 16 and the panels 14 with the upstanding flanges 31 and 32 around the side and end edges thereof provide double protection against a leaking roof, for if water should get under the panel connectors 16, sockets 60 and ridge cap 15 where they seat against the outer surfaces of the panels, the water will still be prevented from entering the building by reason of the presence of the upstanding panel guard flanges 31 and 32.

From the foregoing description, it will be seen that I have provided a new and improved roof of a structural character such that it may be factory fabricated of a few assemblies which may be quickly and consequently inexpensively erected at the building site and yet be leakproof. These fabricated roof assemblies include a ridge member which may be lowered in place as a unitary structure in retainers carried by the end wall and solely restraining movement of the ridge member. The roof assemblies also include a new and improved roof panel having a water guard flange around edges thereof to insure a leakproof roof. Furthermore, the roof includes panel connector members of a character to enclose the panel guard flanges in a manner to insure further a weathertight roof. In addition, I have provided a new and improved panel connector and ridge cap carrying individual closure members which connect the panel connector members to the ridge cap in a manner to insure weathertight joints therebetween.

I claim:

1. In building roof construction, the combination comprising, a ridge member supported on end walls of a building, roof panels extending from side walls of the building and being supported adjacent their inner edges on the ridge member, a ridge cap member seating on the panels on opposite sides of and overlying the ridge member, means holding the ridge cap member and the panels together, a plurality of panel connector members extending laterally from the ridge cap member seating on the panels in overlying relation respectively to the joints therebetween, means holding the plurality of panel connector members and the panels together, and a plurality of laterally projecting extension panel connector members respectively forming weathertight joints with the inner ends of the first plurality of connector members and being carried by the ridge cap member.

2. In building roof construction, the combination comprising, a pair of socket retainers supported respectively on opposite end building walls, a ridge member having opposite end portions respectively supported in the socket retainers and being solely held thereby against side and end

movement, a pair of spaced roof panels on each side of the ridge member extending from opposite side walls to the ridge member, hangers supported by the ridge member and being carried by the panels, said hangers having spaced elements contiguous to oppositely facing surfaces of the ridge member, a ridge cap member overlying and extending longitudinally of the ridge member, the ridge cap member seating on the roof panels on opposite sides thereof, means holding the ridge cap member down against the roof panels, a pair of panel connector members respectively overlying the joints between the roof panels of each pair, the pair of panel connector members respectively seating on the pairs of panels, means for holding the panel connector members and the roof panels together, flanges extending along the inner and side edges of each of the panels laterally from the upper sides of the panels into the ridge cap member and into the panel connector members respectively, and a plurality of extension panel connector members respectively forming weathertight joints with the inner ends of the first panel connector members and being carried by the ridge cap member.

3. In building roof construction, the combination comprising, a ridge member having a side and having an upper portion, a roof panel having one edge disposed toward the side of the ridge member, and a hanger member carried by the roof panel adjacent the said edge thereof, said hanger member including a hook-shaped portion hooked over the upper portion of the ridge member.

4. In building roof construction, the combination comprising, a roof panel, a hollow panel connector member having a seating surface engaging the outer surface of the roof panel, means for holding the seating surface of the hollow panel connector member tightly against the outer surface of the roof panel, a guard member extending along one edge of the hollow roof panel and being directed outwardly from the outer side surface thereof into the hollow panel connector member, and a facing strip extending along the said one edge of the panel reinforcing the guard member.

5. In building roof construction, the combination comprising, a ridge member having an upper portion, a roof panel having one edge disposed toward the side of the ridge member below the upper portion thereof, a hanger member carried by the roof panel adjacent said one edge engaging over the upper portion of the ridge member, a hollow ridge cap member overlying the upper portion of the ridge member seating on the upper surface of the roof panel, means holding the hollow ridge cap member down tightly against the upper surface of the roof panel, and a guard flange carried by the roof panel against the inner side surface of the hanger member extending upwardly into the hollow ridge cap member.

6. In building roof construction, the combination comprising, a ridge member, a pair of panels having opposed edges and supported adjacent other corresponding edges thereof on the ridge member, means co-operable with the ridge member to hold the panels thereto, a panel connector member connecting the panels together adjacent the opposed edges thereof, and an extension connector member in overlapping relation with an end portion of the panel connector member and said means together.

7. In building roof construction, the combina-

tion comprising, an elongated ridge member, a pair of panels having opposed edges extending transversely to the ridge member and supported adjacent other corresponding edges thereof on the ridge member, a ridge cap member seated on the panels adjacent and extending longitudinally of the ridge member, a panel connector member extending laterally to the ridge cap member connecting the panels together adjacent the opposed edges thereof, and an extension connector member carried by the ridge cap member in overlapping relation with one end of the panel connector member.

8. In building roof construction, the combination comprising, a roof panel, a guard flange carried by the panel adjacent one edge thereof extending above the panel upper surface for obstructing flow of water to the edge of the panel, and a hollow panel connector member fitting over the upstanding guard flange and seating inwardly thereof on the upper surface of the panel, and a facing strip reinforcing the guard flange extending into the panel connector member.

9. In building roof construction, the combination comprising, a pair of panels having adjacent opposed edges and having adjacent corresponding edges transverse to the opposed edges, guard flanges extending along the opposed edges and extending along the adjacent corresponding edges of the pair of panels, the guard flanges extending away from the outer corresponding sides of the panels, a hollow panel connector member seating against the said corresponding sides of the panels enclosing the guard flanges extending along the opposed edge of the pair of panels, a ridge cap member seating on the said corresponding sides of the panels adjacent the said corresponding edges, the ridge cap member enclosing the guard flanges along the said corresponding edges of the pair of panels, the panel connector member having an inner end disposed toward the ridge cap member, an extension connector member receiving an inner end portion of the panel connector member and being connected to the ridge cap member, and facing strips extending along the opposed and along the corresponding edges of the panel reinforcing the guard flanges.

10. In building roof construction, the combination comprising, a pair of brackets respectively supported on opposite end walls of a building, a ridge member extending between and supported by said brackets, and a pair of socket members respectively receiving opposite end portions of the ridge member, the socket members solely restraining movement of the ridge member and being carried by the brackets.

11. A ridge cap member for use in building construction having a ridge member and having spaced roof panel connector members extending laterally therefrom comprising, a top wall, opposite side walls joined to the top wall and cooperating therewith to cover the ridge member, and longitudinally spaced extension connector members joined to and extending laterally from the said side walls to close adjacent ends of the panel connector members.

12. A ridge cap for use in a building having a

ridge member and roof panel connector members extending laterally therefrom comprising, a ridge cap member for covering the ridge member, and a plurality of laterally extending hollow extension connector members carried by the ridge cap member for respectively receiving and closing end portions of the panel connector members.

13. A roofing element comprising, a rectangular panel, guard flanges extending along three edges of the panel in co-planar relation therewith extending above the upper surface of the panel to obstruct flow of water past the panel edges thereof, facing strips secured against the opposite pair of the three edges extending above the upper surface of the panel in contact with the outer surface of the guard flanges, and a panel hanger including a web portion secured flat against the other of the three edges of the panel, the web portion extending above the upper surface of the panel in contact with the outer surface of the guard flange.

14. In a building construction including a ridge member and a roof panel, a hanger member attaching the roof panel to the ridge member and comprising a web portion facing one edge of the roof panel, a lower seating portion joined to and extending laterally from the web portion in agreement with the underside of the roof panel, and an upper portion joined to the web portion and disposed on the opposite side thereof from the seat portion, the upper portion co-operating with the web portion to form a downwardly facing channel hook engaging over the ridge member.

15. In a building roof construction, the combination comprising, a ridge member having an upper portion, a roof panel having one edge disposed toward the side of the ridge member below the upper portion thereof, a hanger member carried by the roof panel adjacent said one edge including a hook-shaped portion engaging over the upper portion of the ridge member, a hollow ridge cap member overlying the upper portion of the ridge member and the hook-shaped portion of the hanger member and seating on the upper surface of the roof panel, connecting means extending between the ridge cap member and the ridge member for holding the hollow ridge cap member down against the upper surface of the roof panel, said connecting means including a threaded member and a nut engaging the threaded member drawing the hollow ridge cap member down tightly against the upper surface of the roof panel whereby the hook-shaped portion is drawn down over and retained over the upper portion of the ridge member.

NOLAN S. BLACK.
